3 Claims. (Cl. 250—41.9)

The present invention relates to improved gas detecting and analyzing methods and apparatus. The methods and apparatus of the present invention are particularly well suited for the detection and analysis of hydrocarbon gases present in the circulating fluid or "mud" used in the drilling of wells which are indicative of the presence of petroleum or natural gas, and for certain other gases, particularly hydrogen. These methods and apparatus provide greater sensitivity and precision in the continuous logging of the gas content of the drilling mud as it recirculates back to the surface of the earth from the bottom of a well being drilled.

During the drilling of a well it is a customary practice to examine the drilling fluid, or mud, to detect the presence of hydrocarbon gases and also hydrogen and other gases. As the circulating mud passes the drill, it picks up cuttings from the drill. Successive elemental volumes of the mud and the cuttings in these volumes retain traces of the hydrocarbon gases present in successive strata through which the drill is passing at the time. By analyzing the gas content of successive volumes of the mud-cuttings mixture soon after they leave the mouth of the well and by correlating these gas content measurements with the successive depths of the drill from which they came, the geologists learn important information on the characteristics of the underground formations through which the drill passes.

The traces of hydrocarbons present in the mixture of mud and cuttings are often very dilute so that extremely sensitive measurements must be made to detect their presence. A great amount of time and effort has been spent by many persons in efforts to further this art of logging of the drilling mud.

The accompanying drawing is a schematic electrical circuit diagram of improved apparatus for detecting and measuring hydrocarbon gases, including automatic programming control mechanism for controlling the scanning of the various hydrocarbon gas constituents.

One of the practices which has been adopted in the logging of drilling mud is the use of mass spectographs to detect and analyze the hydrocarbon gases liberated from the mixture of drilling mud and cuttings. In particular, linear-type electrostatic mass separators are finding wide-spread acceptance. In these instruments, samples of these gases are drawn into a highly evacuated chamber and are ionized by bombardment with a stream of electrons in a conventional type ionization chamber. The ionized molecules of any gases present are then accelerated out of the ionization chamber through a set of electrostatic lenses which collimates the beam of ions. The ion beam then passes through aligned apertures in a row of flat plates. Successive plates along the line are spaced progressively farther apart, and the individual plates are energized by a radio frequency potential of predetermined frequency. Because ions of different mass-to-charge ratios (m/e) accelerate at different rates, only ions of a certain selected mass-to-charge ratio remain in phase with the radio frequency potential for

any given frequency as they pass successive plates and reach maximum velocity. At the end of the acceleration path is positioned a deflector plate and a screen with a narrow slit therein. Only ions having the maximum velocity are properly deflected so as to pass through this slit. Thus, ions of the selected mass-to-charge ratio are separated from any others present. These selected ions form an ion current which is then amplified and measured as an indication of the amount of the corresponding gas present. In order to measure the concentrations present of ions of different weights, the radio frequency applied to the mass spectrometer is changed to different values. Each predetermined frequency value which is used corresponds to a predetermined selected ion mass.

Expressing this in somewhat different terms, each different sample of a gas mixture obtained over a volume of drilling mud contains several different gases. There are usually relatively heavy concentrations of the atmospheric gases such as nitrogen, oxygen, carbon dioxide, and water vapor. In addition, traces of one or more of the following hydrocarbon gases and also hydrogen and other gases, may be present: hydrogen, methane, ethane, propane, butane, pentane, and hexane. When any one of these gases is present and is ionized, the apparatus gives a peak reading or peak value indication at a frequency setting corresponding with the predetermined radio frequency which selectively accelerates these ions. This peak value indication is termed the mass peak for the particular ionic mass under consideration.

Considering an atom of oxygen as having a mass of 16 units, these listed gases have the following mass values:

	Gas	Chemical Formula	Mass
40	Hydrogen	H_2	2
	Methane	CH_4	16
	Ethane	C_2H_6	30
	Propane	C_3H_8	44
	Butane	C_4H_{10}	58
	Pentane	C_5H_{12}	72
	Hexane	C_6H_{14}	86

45 In the methods and apparatus described herein as illustrative embodiments of the present invention provision is made for measuring in sequence the mass peaks of a plurality of different gases. The apparatus automatically switches from measurement of one mass peak to measurement of the next in a predetermined sequence and then recycles automatically. When set for automatic sequential operation this apparatus described herein measures six mass peaks in succession for durations of approximately ten seconds each. At the end of each minute, the apparatus automatically begins repeating the sequence.

In these methods and apparatus provision is also made for repetitively measuring paired combinations of mass peaks. The apparatus automatically switches from measurement of one mass peak to the other and back again. Each mass peak is measured for thirty seconds, and at the end of each minute, the cycle begins again.

In addition, the apparatus described can be set manually for continuous measurement, i.e. monitoring of any one of six mass peaks. Whenever desired the apparatus may be immediately changed from monitoring one mass peak to another.

Among the many advantages of the methods and apparatus of the present invention are those resulting from the fact that they enable sensitive and accurate measurements to be made right at the well site while the drilling continues. The automatic sequencing from one

mass peak to another provides important analytical information concerning the various gas constituents which are present. Continuous logging of the drilling mud is facilitated and the magnitudes of the various mass peaks are analyzed in a way which greatly helps the geologist in obtaining an early detection of underground petroleum and gas deposits.

The ratios of the concentrations of pairs of gas constituents which are present, and in particular between methane and the others, yields valuable information concerning the petroleum and gas content of the formations being drilled. The automatic switching between any one of these mass peaks and one of the other mass peaks provides a continuous measure of the ratio between the concentrations of the two gases being monitored and shows their concentrations in the gas sample.

In this specification and in the accompanying drawing, are described and shown embodiments of the improved gas detecting and analyzing methods and apparatus of the present invention and various modifications thereof are indicated, but it is to be understood that these are not intended to be exhaustive nor limiting of the invention, but on the contrary are given for purposes of illustration in order that others skilled in the art may fully understand the invention and the manner of applying the method and apparatus in practical use so that they may modify and adapt it in various forms, each as may be best suited to the conditions of a particular use.

The various objects, features, and advantages of the present invention will be more fully understood from a consideration of the following detailed description of methods and apparatus embodying the present invention in conjunction with the accompanying schematic circuit diagram of improved apparatus for detecting and measuring hydrocarbon gases.

In operation the circulating hydraulic fluid 10 after it issues from the mouth of a well being drilled is conveyed through channel means 11, shown as a pipe seen in cross section. Connected to the hydraulic fluid channel is a gas sampling tube 12 feeding through a valve 14 to a mass spectrometer 16 schematically represented in block form as being a linear-type mass separator tube.

In order to select the desired mass peak, a radio frequency oscillator 18 has its output coupled into the mass spectrometer 16. The radio frequency potential is applied in opposite phase relationship to alternate plates along the ion path within the mass spectrometer by coupling one of the oscillator output terminals 19 to alternate plates and by coupling the other terminal 20 to the intervening plates. One of these output terminals may be connected to the common return or ground circuit of the apparatus as indicated by the ground symbol appearing at the terminal 19.

A resonant circuit, generally indicated at 22, controls the frequency of the oscillator. This resonant circuit includes an inductance winding 24 shunted by an adjustable capacitor 26. One side of the resonant circuit is connected by a lead 28 to the common return circuit and the other side of this resonant circuit is connected by a lead 30 to a six-position switch 32. This switch is arranged effectively to couple any selected one of six adjustable capacitors 34, 35, 36, 37, 38, and 39 between the leads 28 and 30, thus tuning the frequency of the oscillator 18 to any one of six selected mass peaks, as may be desired by the operator. This switch 32 is driven by means of a mechanical linkage schematically indicated at 40 driven by a rotary stepping solenoid 42. The operation of this rotary stepping solenoid is explained in detail further below.

For the purpose of eliminating spurious responses in the amplifier circuits and to enable easier amplification, a modulator 44 feeds an alternating voltage into the mass separator tube. This modulator applies an alternating

voltage of a distinctive frequency to a grid circuit arranged to modulate the ion beam in the tube. The modulator frequency is a convenient value of relatively low frequency compared with the oscillator 18 and is 5 distinctively different from 60 cycles or a harmonic thereof. For example 160 cycles per second may be used to advantage.

The resultant modulated beam of ions of selected mass produces an alternating voltage signal which is initially amplified in a pre-amplifier 46. The signal is then fed through a pre-set attenuator circuit 48 and through a main amplifier circuit 50 to a synchronous demodulator 52 which is also under the control of the modulator 44 as indicated schematically by the connection 54. From the demodulator a unidirectional current signal is fed by means of a pair of connections 55 and 56 to a recording pen mechanism in a chart recording instrument 58. Thus, the recorder plots values as a function of the magnitudes of the mass peaks being measured.

10 In order to calibrate the apparatus to yield recorded values as functions of the quantities of the various hydrocarbon gases present, samples of known mixtures of gases are fed into the mass separator tube. The pre-set attenuator 48 is then set to produce the desired reading 15 at the recorder for each mass peak.

20 In certain instances it is desirable to provide for suppression of the background of each mass peak. This function is obtained by a zero suppression circuit schematically indicated in block form at 60. This zero suppression circuit feeds a predetermined fraction of the modulator voltage into the pre-amplifier 46 so as to prevent the recorder from giving any indication when the values of the individual mass peaks fall below the 25 respective zero suppression levels chosen for them.

30 In order automatically to control the operation of the apparatus, an automatic peak programming circuit is utilized, as indicated at 62 in the center of the drawing. This peak programming control circuit can be adjusted 35 readily for any one of three modes of operation by means of a manually operable ganged five-position switch 63 having six contact arms 64, 65, 66, 67, 68 and 69. When this switch is in its extreme left-hand, or counterclockwise position, the peak programming control circuit is adjusted for continuous scanning or monitoring 40 of any one of six mass peaks. The particular mass peak desired for monitoring is selected manually by turning a manual selector switch 70 including first and second ganged sections, 71 and 72, respectively, into any one of 45 six positions. This left-hand position of the switch 63 is 50 called the "manual" position.

The switch 63 can be turned through a stop position at which no indications are recorded to a center position called the "pairs" position. When the switch 63 is in the pairs position, a second mode of operation is produced. The apparatus automatically repetitively scans 55 one mass peak for thirty seconds and then scans any one of five other desired mass peaks for thirty seconds. Under most conditions, for typical drilling operations it is found most advantageous to include methane as one of the 60 pairs of mass peaks being monitored as giving the most sensitive indication. But occasionally one of the other light gases such as hydrogen, ethane, or propane may be used to advantage in these paired combinations, for example, when the drilling is approaching a formation 65 in which the ratio between one of these other light mass peaks and another particular mass peak is expected to show a marked variation from the average. The other mass peak to be scanned in a paired combination with one of these light mass peaks is determined by the operator 70 by turning the manual selector switch 70 to the desired position.

75 By turning the switch 63 further to the right, it passes through a second "stop" position and then reaches the "sequence" position producing automatic repetitive se-

quencing of the apparatus through any desired six mass peaks, dwelling 10 seconds on each.

In order to control the position of the rotary stepping solenoid 42, an automatic selector switch, generally indicated at 80 is coupled to the solenoid by means of the drive linkage 40. This switch 80 includes two sections 81 and 82, which are respectively identical with the sections 71 and 72 of the manual selector switch 70. When set for scanning of a pair of mass peaks, for example, including methane and one of the other hydrocarbons listed above, the selector switch 80 is automatically positioned by the stepping solenoid 42 in accordance with the setting of the manual selector switch 70 during alternate 30-second periods. During the intervening 30-second intervals, the sequencing control 62 automatically scans the methane mass peak, as will be explained further below.

For signalling the mass peak being scanned, a six-position signal light control switch 84 has a rotating contact arm 86 connected by a lead 87 to one side of a low voltage source, shown as a 6.3 volt alternating current source. Six signal lamps 88, 89, 90, 91, 92, and 93 are connected to respective individual contacts of the switch 84 and are all connected through a lead 94 to the other side of this low voltage source.

For recording a steady mark on the record chart in the recorder 58, as an indication of which mass peak is being scanned, a direct current signal of fixed value is produced by a function marker control switch 96. This switch 96 is a six-position switch and has a contact arm 98 also driven by the linkage 40 in synchronism with the other switches 86, 80, and 32.

The six contacts of the switch 96 are connected to six spaced points along a resistance potential divider 100 which has a direct voltage developed across it by a rectifier 102 and a filter circuit 104 energized from the leads 87 and 94. As the contact arm 98 is positioned on successive contacts in the switch 96, a successively different steady voltage is fed through a pair of leads 105 and 106 to a function indicating pen drive mechanism in the recorder 58. This produces a continuous recorded mark which steps from one fixed value to another as different mass peaks are scanned.

Automatic sequence scanning method and operation

For purposes of explanation of the operation of the peak program control 62, assume that the switch 63 is turned to the sequence position. A synchronous type motor 110 geared to produce an output shaft speed of 1 revolution per minute is energized with 115 volt, 60 cycle current from a pair of mains 111 and 112. The motor energizing circuit is traced from the main 111 through a line 113 and a fuse 114 and a lead 115 to one terminal of the motor 110. The return from the other terminal of the motor passes along leads 116 and 117 and through the right contact 118 to the switch arm 69 and back through the line 119 to the main 112. The motor turns five cams 120, 121, 122, 123, and 124, respectively operating five single-pole micro-switches 125, 126, 127, 128, and 129. The first four of these switches 125-128 are double-throw switches, and the associated cams 120-123 are arranged to move their contact arms in synchronism back and forth, dwelling in each closed position for 30 seconds.

The fifth micro-switch 129 is a single-throw switch and its operating cam 124 has six raised areas arranged to swing the contact arm 130 to the left, or closed position six times each minute, holding the switch 129 closed for approximately 10 seconds upon each closure. This switch arm 130 completes a circuit from a junction point 131 between a capacitor 132 and a rectifier 133 to a sequence control bus 134 connected to the right or sequence contacts 135, 136, 137, and 138, of the first four sections of the manual switch 63.

With the switch 63 in the sequence position, as assumed

above, the switch arms 64, 65, 66, and 67 engage the contacts 135, 136, 137, and 138, respectively, thus connecting the bus 134 to each of four control lines A, B, C, and D, respectively. These control lines run to four contacts a-1, b-1, c-1, and d-1 of the switch section 81, respectively, and also to four contacts a-2, b-2, c-2, and d-2 of the switch section 82. Depending upon the position of the rotatable switch disk 140 of the switch 82, one or more of the control lines A, B, C, and D are connected to a switch contact 141. A resistor 142 in series with a capacitor 143 is connected from the contact 141 to the power line 119, and the control lines A, B, C, and D are connected by the contact 141 to a wire 144 running to one terminal of the rotary stepping solenoid 42. A wire 145 runs from the other terminal of this solenoid to the sequence (right) contact 146 of the fifth section of switch 63.

When the manual switch arm 69 engages the contact 118, it also completes a circuit from one A.C. power line 119 through the lead 116 and the rectifier 133 and capacitor 132 in series to the other A.C. power line 113. Thus, the capacitor 132 is charged and the junction point 131 assumes a negative potential with respect to the line 113 and with respect to the switch arm 68 connected thereto. Upon closure of the cam-actuated switch 129, this capacitor is discharged through one or more of the control lines A, B, C, and D and through the rotary solenoid 42. The surge of current causes the solenoid to turn the linkage 40 to the next sequential position where it remains for 10 seconds, thus scanning one of the mass peaks for this period of time.

When the cam-actuated switch 129 momentarily opens at the end of the first 10-second period, the capacitor 132 recharges. Upon the next closure of the switch 129, this capacitor again discharges, advancing to the next mass peak for a 10-second scanning period. In this way an automatic cycle of one minute duration is obtained, repetitively scanning in sequence six mass peaks for equal periods of approximately 10 seconds each.

The particular mass peaks chosen are predetermined by adjustment of the various tuning capacitors 26, 34, 35, 36, 37, 38, and 39 controlling the frequency of the oscillator. It is usually most desirable to select as mass peaks those representative of six of the seven following gases: hydrogen, methane, ethane, propane, butane, pentane, and hexane. The particular mass peaks which are usually found most useful do not all correspond exactly with the relative molecular weights as listed above, for the following reasons.

During the ionization of the various hydrocarbon gas molecules some of them are broken up or fractionated to a greater or lesser degree under the impact of the ionizing beam of electrons. The result is a fractionation pattern involving several mass peaks for each type of molecule. Because of the relatively large numbers of molecules of each type involved, the fractionation pattern of mass peaks for each type of molecule is a fixed pattern, resulting from statistical averaging over large numbers. Many of the mass peaks resulting from the fractionation of the heavier molecules, for example, such as pentane and hexane coincide with the principal mass peaks of the lighter molecules. Thus, in reading the relative values of the six mass peaks allowance is made for the contributions to the lighter mass peaks by the fractionation patterns of the various heavier molecules. The fractionation pattern of any given type of molecule is calibrated by introducing a pure sample of that gas and measuring relative magnitudes of the various mass peaks resulting from the ionization process.

In addition, the atmospheric gases, which are usually present in far greater concentrations than the hydrocarbon gases being detected and measured contribute various mass peaks. The mass peak 16 of oxygen coincides with the principal mass peak of methane, and so it is convenient to take advantage of methane's fractionation pat-

tern and use mass peak 15 instead. This mass peak 15 results from ionizing collisions of methane molecules in which one or the four hydrogen atoms is knocked off, and it is the largest side mass peak (i.e. other than the principal one at mass 16 for methane under usual operating conditions.

Because of coincidence with mass peaks in the fractionation patterns of heavier molecules, it is usually desirable to avoid mass peak 44 for a measure of the propane concentration. Instead, the use of mass peak 42 is usually a more sensitive and accurate indication of propane concentration.

In summary of the sequence operation, the apparatus automatically scans any six desired mass peaks in repetitive cycles of 10 seconds each. The mass peaks of 2, 15, 30, 42, 58, 72, and 86 are particularly useful for indicating respective ones of the eight listed gases. At the end of each minute the cycle automatically begins again. At the same time, the signal lamps indicate at a glance which mass peak is being scanned, and the function pen records a fixed value indication on the recorder chart showing which mass peak is being scanned.

Automatic pairs scanning method and operation

For automatic pairs scanning, the manual control switch 63 is turned to its center position. The motor 110 is now energized through the switch arm 69 and the center or "pairs" contact 148. Also, the other terminal of the solenoid 42 is now connected through a rectifier 150 and a lead 152 to the "pairs" or center contact of the fifth section of the switch 63, which is engaged by the arm 68 and thus completes a circuit to the power line 113.

Directing attention to the first four sections of the manual control switch 63, it is seen that the contact arms 64, 65, 66, and 67, respectively, when in the "pairs" position complete circuits from the control lines A, B, C, and D to the switch arms 155, 156, 157, and 158 of the first four cam-actuated switches 125, 126, 127, and 128, respectively. The four associated cams 120, 121, 122, and 123, respectively, swing these switch arms into engagement with the right contacts for approximately 30 seconds during each minute of operation and into engagement with the left contacts for the remaining 30 seconds during each minute.

When the four switch arms 155, 156, 157, and 158 are swung to the right, the three control lines A, B, and C are connected to a bus 159 running to the lead 116 and thus are coupled to the power line 119. However, the control line D is left unconnected from the bus 159, for the right contact 154 of the switch 128 is unconnected.

In effect then, the control lines A, B, and C are energized with voltage from the A.C. power line 119. Thus, whenever the switch disk 140 engages any one of the contacts a-2, b-2, or c-2, a circuit is completed from the power main 112 through the solenoid 42 and through the rectifier 150 to the switch arm 68 and thus back through the fuse 114 to the other power line 113. This energizes the solenoid causing it immediately to turn to the next position. The switch disk 140 has three contact lugs x, y, and z and three depressions therebetween. The lug "x" is wide enough to engage only one of the contacts a-2, b-2, c-2 or d-2. The depression between lugs x and y is wide enough simultaneously to avoid two of these contacts. The lug y is wide enough simultaneously to engage two of these contacts, while the depression between lugs "y" and "z" will only avoid one of these contacts. The lug "z" is wide enough simultaneously to engage three of these contacts, and the depression between lugs "z" and "x" is wide enough simultaneously to avoid three of these contacts.

By virtue of this shape of the contact disk 140, the solenoid 42 is energized and turns quickly from position to position until the lug "x" engages the dead contact d-2 and the adjacent widest depression avoids all three

of the energized contacts a-2, b-2, and c-2. In this position the rotary stepping solenoid 42 is de-energized and ceases turning.

Thus, the oscillator 18 is automatically tuned to a preselected mass peak, usually one of the lighter mass peaks, for example, such as the methane mass peak 15, and the scanning of the methane mass peak continues for approximately 30 seconds. Then, during the next 30 second period, the four cams 120, 121, 122, and 123 move the switches 125, 126, 127, and 128 to their left positions, connecting the control lines A, B, C, and D, respectively, to four control lines E, F, G, and H which run to the contacts e-1, f-1, g-1, and h-1 and e-2, f-2, g-2, and h-2 of the manual selector switch 70. The contact disk 160 of the switch section 72 has three lugs w, v, u, and is identical in configuration with the switch disk 140. The lug "w" is wide enough to engage only one contact; the lug "v" is wide enough to engage two contacts simultaneously, and the lug "u" is wide enough to engage three contacts simultaneously. A longer contact 161 always engages the disk 160 and is connected by a lead 162 with the power line 119. Thus, depending upon the angular position of the manual selector switch 70, one or more of the control lines E, F, G, or H and consequently one or more of the corresponding control lines A, B, C, and D are energized from the power line 119.

The rotary stepping solenoid 42 is correspondingly energized and moves around to a position in which the lug "x" is at an angular position corresponding with the angular position of the depression between the lugs "u" and "v" of the contact disk 160. In other words, the solenoid 42 is energized until depressed areas in the disk 140 are opposite whichever ones of the contacts a-2, b-2, c-2, and d-2 are being energized from the contact 161 as a result of the angular position of the switch 70.

In effect then, the solenoid 42 and switch 80 are made "slave" to the position of the manual selector switch 70 during the alternate 30-second intervals when the four cam-actuated switches 125, 126, 127, and 128 interconnect the control lines A, B, C, and D respectively, with the control lines E, F, G, and H.

In this way an automatic scanning of the methane mass peak 15 in paired combination with any one of the other mass peaks is obtained, the manual control switch 70 being turned to select whichever one of the other mass peaks is desired. Usually the methane and ethane mass peaks are used as a paired combination because they yield the most sensitive indications of the presence of petroleum or gas.

Manual operation

By turning the control switch 63 to its left or manual position the motor 110 is de-energized. The lead 152 from the rectifier 150 is again connected to the power line 113 by means of the switch arm 68. At the same time, the four switch arms 64, 65, 66, and 67 directly connect the control lines A, B, C, and D respectively to the control lines E, F, G, and H. This makes the automatic selector switch 70 and solenoid 42 continuously operate in "slave" relationship to the angular position of the manual selector switch. Whenever the operator turns the manual selector switch to select a different mass peak, the solenoid immediately turns the linkage 40 to the proper position for scanning of the selected mass peak.

In order to tune the zero suppressor 60 and pre-set attenuator 48 to various values corresponding with the desired calibration of the apparatus, another pair of switches identical with the switch 70 may also be driven by the linkage 40. Then an automatic selector switch and a rotary stepping solenoid such as the switch 70 and the solenoid 42 are included in the suppressor circuit and in the attenuator circuit. Thus, the tuning of the suppressor and attenuator is made automatically to follow the tuning of the selector switch 80.

From the foregoing it will be understood that the improved gas detecting and analyzing methods and apparatus

of the present invention described above are well suited to provide the advantages set forth, and since many possible embodiments may be made of the various features of this invention and as the method and apparatus herein described may be varied in various parts, all without departing from the scope of the invention, it is to be understood that all matter hereinbefore set forth or shown in the accompanying drawing is to be interpreted as illustrative and not in a limiting sense and that in certain instances, some of the features of the invention may be used without a corresponding use of other features, all without departing from the scope of the invention.

What is claimed is:

1. Apparatus for logging the hydrocarbon gas content of mixtures of unknown gases comprising measuring means having a plurality of different operating conditions and selectively measuring the relative concentrations of the following six hydrocarbon gases: methane, ethane, propane, butane, pentane, and hexane, each operating condition corresponding with the measurement of one of said gases; first switch means connected to said measuring means and having six positions each one corresponding with and producing one of said measurements; second switch means having a pair of positions, one of said pair corresponding with measurement of methane, and the other of said pair interconnecting said second and first switch means and producing a measurement controlled by said first switch means; and cyclic drive means operating said second switch means back and forth between said pair of positions.

2. Apparatus for logging the hydrocarbon gas content of mixtures of unknown gases comprising ionizing means; measuring means having a plurality of different operating conditions and selectively measuring the relative concentrations of ions of masses 15, 30, 42, 58, 72, and 86, each operating condition corresponding with and controlling the measurement of a selected one of said ion masses; first programming switch means connected to said measuring means and having six positions each one producing

a selected one of said measurements; second programming switch means connected to said measuring means and having at least two operating positions, one of said latter positions producing the measurement of ion mass 15 and another of said latter positions interconnecting said second and first switch means and producing a measurement of an ion mass selected by said first switch means; and cyclic drive means operating said second switch means repetitively from one to another of said latter positions.

3. Apparatus for logging the gas content in drilling "mud" comprising gas conducting means for withdrawing a gaseous mixture including gas constituents from the mud, ionizing means for ionizing said gaseous mixture, radio frequency mass selecting oscillator circuit including frequency controlling elements and having a plurality of different operating frequencies as controlled by said frequency controlling elements, each frequency indicating the relative concentration of a particular gas in said mixture, first and second switching mechanisms, a manual selector control connected to said switching mechanisms for selectively placing said first and second switching mechanisms in operation, and a motor drive connected to said first and second switching mechanisms and under the control thereof, said motor drive being coupled to said frequency controlling elements and when said first switching mechanism is operative cyclically switching between two frequencies, dwelling at each frequency for predetermined lengths of time, and when said second switching mechanism is operative sequentially switching to each of said different operating frequencies, dwelling at each frequency for the same period of time.
